UNITED STATES PATENT OFFICE.

HARRY M. BROWN, OF BROOKLYN, NEW YORK, ASSIGNOR TO SPRING STOPPER COMPANY, OF BROOKLYN, NEW YORK, A CORPORATION OF DELAWARE.

GLASS-SEVERING IMPLEMENT.

1,346,528.

Specification of Letters Patent. Patented July 13, 1920.

Application filed August 20, 1919. Serial No. 318,670.

To all whom it may concern:

Be it known that I, HARRY M. BROWN, a citizen of the United States, residing at Brooklyn, in the county of Kings and State 5 of New York, have invented a new and useful Improvement in Glass-Severing Implements, of which the following is a specification.

This invention is in the nature of an implement for severing glass; and the primary 10 object of the invention is to provide an implement adapted to the purpose of severing or cracking off the end-portions of the necks of carboys or other glass containers.

It may be stated preliminarily that in the manufacture of carboys or other large glass containers it is customary to form the carboy-body by suitable operations, including a blowing operation on a pipe, the carboy-body being thus provided with a neck-portion, and the neck-portion is then placed in a suitable mold and "metal" or molten glass is charged therein and suitably pressed to form the head or mouth of the 20 container. In this operation the mouth-portion of the container is given the desired contour, and may be provided with internal 25 or external threads, if desired.

In practice, it is desirable to make the carboys of substantially uniform height and 30 give to the neck-portion an end edge which lies in a plane substantially perpendicular to the axis of the carboy. This is accomplished by breaking or cracking off the excess 35 portion of the neck which the carboy has as the result of the method of manufacture usually employed.

The desired object is readily attained by 40 means of the improved implement shown in the accompanying drawing, which illustrates the preferred embodiment of my invention.

In the drawing—

Figure 1 represents a plan view of the 45 improved implement, one of the jaws of which is shown in section; and Fig. 2, an elevational view of the implement, illustrating the manner in which it is applied to a carboy-neck in the operation of severing 50 the neck, one of the jaws being shown brokenly.

In the construction illustrated, A represents the neck of the carboy or other glass container; and B represents the improved 55 implement adapted for severing the neck or breaking off the excess portion of the neck.

The device B comprises a pair of levers B' and B² which are pivotally connected together by means of the pintle 1. In the form shown, the lever B' has a substantially semi-circular jaw-portion 2, an offset pivot-portion 2^a, and a handle 2^b. Similarly, the lever B² has a companion jaw-portion 3, an offset pivot-portion 3^a, and a handle-portion 3^b. 60

The levers are made of steel or other suitable metal, the handle-portions being equipped with suitable non-conductive grips, as shown. In each case, the jaw-portion is preferably tubular in cross-section, but 70

formed with a V projection at its inner or concave side, as indicated at 4, thus providing a comparatively sharp edge which is adapted to bite into the hot glass. Each jaw is thus provided with a channel 5 75 through which water may be circulated; and at the inner or cutting edge of each jaw are provided small perforations 6, enabling the water to spurt against the glass and follow the groove in the glass produced by the jaws 80 when they are pressed about the neck of the container. The extremities of the jaws are equipped with tubular members, or nipples, 7, equipped with inlet and outlet hose 8 and 85

9. The nipples 7 preferably lie in the plane of the jaws and extend in opposite directions from the end-portions of the jaws. At their base-portions, the jaws are provided with laterally projecting nipples 10, which communicate with the channels 5 of the 90

jaws. The nipples 10 are equipped with elbows 11 and these elbows communicate with each other through a flexible hose 12, so that the water can circulate through the jaw 3, thence through the hose 12, thence through 95 the jaw 2, and may escape through the hose 9. The inlet hose 8 may be equipped with a valve (not shown) for regulating the water pressure. 100

The preferred method of employing the implement is to apply it to the neck of the carboy after the carboy has been blown and is still hot, and force the jaws into the soft glass at or adjacent the blow-pipe. By pressing the handles together, so that the jaws squeeze the neck of the carboy, grooves are formed in the neck, and the water spouting against the glass and following the biting edges of the jaws rapidly chills the glass and causes the neck to crack where the jaws 105 come in contact with the glass. In this manner, the excess glass may be readily removed 110

and the neck-portion of the carboy may be given a comparatively true edge, thus placing it in proper condition for the subsequent operation of applying the head, or mouth-portion, of the carboy by any approved process.

The foregoing detailed description has been given for clearness of understanding only and no unnecessary limitation should 10 be understood therefrom, but the appended claims should be construed as broadly as permissible, in view of any prior art which may exist.

What I regard as new and desire to secure 15 by Letters Patent is:

1. An implement of the character set forth, comprising a pair of pivotally-connected levers equipped with jaws provided with channels and having perforations opening at their biting surfaces, and means for 20 circulating cooling fluid through said channels.

2. An implement of the character set forth, comprising a pair of pivotally-connected levers equipped with concavo-convex 25 tubular jaws provided on their inner sides

with V-shaped biting edges and having perforations therethrough, and means for circulating water through said channels.

3. An implement of the character set 30 forth, comprising a pair of pivotally-connected levers equipped with hollow jaws provided at their inner walls with perforations, means for admitting water to one of said jaws and flexible tubular connection 35 between the base-portions of the jaws through which water may circulate through the other jaw, and means for conducting the water away from the last-mentioned jaw.

4. An implement of the character set 40 forth, comprising a pair of pivotally connected levers equipped with tubular jaws having their end-portions provided with nipples disposed in the plane of the jaws and having their base-portions provided with 45 laterally-projecting nipples, a flexible hose connecting said laterally-projecting nipples and lying in a plane parallel with the handles of the implement, and flexible hose connected with said first-mentioned nipples.

HARRY M. BROWN.
